UNITED STATES PATENT OFFICE.

EUGENE FRANCIS CONSIDINE, OF WALKERVILLE, ONTARIO, CANADA.

PILING.

Application filed October 23, 1926 Serial No. 143,770.

The present invention relates to wood piling and preservation of the same.

Heretofore, it has usually been customary in the treatment of piles to preserve them, to 5 treat the whole pile. This is an unnecessary waste of the preservative material in many cases, as under most conditions, that part of the pile which is buried in the earth does not deteriorate even when not treated. In 10 substantially all cases it is that portion of the pile which is subjected to successive wetting and drying that deteriorates. This portion is benefitted by treatment with creosote or other preservative.

15 The treatment of whole piles, particularly those of unusual length requires great outlay for apparatus and treating liquid. And the driving of extremely long piles also requires unusual apparatus.

20 Among the objects of the present invention therefore, is to overcome these difficulties and effect an economy in both the preserving and placing of piling, particularly piling of unusual length.

25 Other objects will readily appear to those skilled in the art upon reference to the following description and drawing in which a preferred form of embodiment of the invention is described and illustrated and in which:—

30 Fig. 1 is an enlarged vertical section of a portion of the pile of Fig. 2.

35 Fig. 2 is a more or less diagrammatic view in elevation of a pile embodying the invention.

As indicated in the drawings the pile is 40 preferably formed of two portions of which the pointed or lower end portion A will be untreated with preservative. The upper end portion B will be of sufficient length to extend down a short distance below the fixed water line. This portion B will be treated with preservative.

45 The two parts are secured together by means of a metal sleeve C into which adjacent ends of parts A and B will extend and

which is secured to these ends by spikes D or other suitable means.

This form of pile is especially useful when it is necessary to drive exceptionally long piles, as the lower portion may be sunk for a considerable portion of its length before attaching the upper portion. This means that with apparatus capable of handling up to a certain length of pile, piles of approximate multiples of that length may be driven, as the present piles may be made in more than two sections with only the upper section of preserved piling.

In those cases where it is necessary to sink 50 very long piles and to drive the lower part independently of the first, it is preferred to provide this part with a ring E to keep the end from splitting or spreading. This ring 55 is left on and the sleeve C put over it.

Further, as it is usual to cut off the upper end of piles to even them or for some other reason, this part may be bored axially for a few feet so that the preservative may penetrate properly that part which becomes the 60 end after the parts is sawed off. The lower end of such a hole is indicated at F.

Having now described the invention and the preferred form of embodiment thereof it is to be understood that the said invention 70 is not to be limited to the specific details herein described and shown but only by the scope of the claims which follow.

I claim:—

1. A sectional wood pile comprising a 75 lower unpreserved section adapted to be completely below water level and an upper section which has been treated with a preservative.

2. A sectional wood pile comprising a 80 lower untreated section, an upper preservative treated section seated thereon, and a metal sleeve extending longitudinally over the adjacent ends to prevent lateral displacement.

EUGENE FRANCIS CONSIDINE.
